UNITED STATES PATENT OFFICE.

WILLIAM W. HANNAH, OF HUDSON, NEW YORK.

IMPROVEMENT IN MARINE CRADLES FOR HOISTING AND LOWERING BOATS.

Specification forming part of Letters Patent No. 146,672, dated January 20, 1874; application filed May 20, 1873.

To all whom it may concern:

Be it known that I, WILLIAM W. HANNAH, of Hudson, in the county of Columbia and State of New York, have invented a new and useful Improvement in Boat Hoisting and Launching Apparatus; and I do hereby declare the following to be a full and exact description of the same, reference being had to the accompanying drawings forming part of this specification, in which—

Figure 1 is a perspective view; Fig. 2, an elevation, showing the boat raised; and Fig. 3, an elevation, showing the apparatus lowered.

Similar letters of reference in the accompanying drawings denote the same parts.

The object of this invention is, primarily, to provide for public use a boat hoisting and launching apparatus for vessels, by means of which a boat can be readily and safely lowered into or raised out of the water, however rough the sea may happen to be; and, secondarily, to so construct the apparatus that it can be used for rescuing persons from the water and hoisting them on board, for hoisting the boat itself in upon deck, and in place of davits or cranes for the permanent suspension of the boat out of the water at the side or stern of the vessel or at the side of the pier or landing. To these ends, my invention consists, first, in a peculiarly-constructed basket or cradle for the support of the boat, which entirely surrounds it, so that the boat or persons falling into the water will be securely held therein without danger of slipping out from the pitching of the vessel; and, secondly, in the combination of said basket or cradle with suitable hoisting and fastening apparatus, substantially as hereinafter set forth.

In the drawings, S is the wall of the vessel or pier; and B is the boat, resting in a cradle or basket, C, the upper part of which is of the shape of a horizontal section of the boat, and slightly larger, the bottom of the cradle being a horizontal rod on which the keel rests, which is suspended, by rods, chains, or ropes r, from the ends of a straight or bent arm or arms, d, articulated to the wall S, and raised or lowered by means of ropes and pulleys h, or a tackle

and fall supported by one or more strong standards, p, suitable provision being made for laying the ropes so as to retain the boat permanently in the position shown in Fig. 2, whenever desirable.

The important feature of my invention consists in the employment of an open basket or cradle for the support of the boat, and entirely surrounding it, so that when the whole apparatus is lowered into the water the boat will float off without any obstacle, and so that, when the boat or any other object in the water is to be secured and hoisted in, the basket or cradle, upon being raised through the water, will secure and raise the same in the manner of a dip-net.

The arms d d when used with the cradle c, as shown in the drawings, may be made to diverge from a single supporting-plate, although I prefer to attach them to the shafts, as represented.

When desirable to hoist the boat in upon deck, or upon the pier, the shaft e, or other pivot, should be arranged nearly or quite at the top of the gunwale or pier, and the pulleys over which the ropes h pass at the top of the standards should be arranged upon a cross-bar connecting the standards, so as to let the arms d swing in between the standards to bring the boat over the deck, when it can readily be lowered to place.

The ropes h may be wound upon a windlass or reel, w, if preferred, to secure their simultaneous and equal movement, and a ratchet and pawl may be provided to prevent any accidental retrograde movement of the mechanism.

I am aware that a marine cradle has heretofore been employed in which two bands pass around the bottom of the boat near its bow and stern, said cradle being raised and lowered by blocks and tackles; and I therefore lay no claim to such invention, as the boat in this case is extremely liable to slide from the ends of such cradle in launching or hoisting it up, or when the boat is suspended from the sides or stern of the vessel, from the rolling or pitching of the latter, the cradle not entirely surrounding and securely holding the boat;

nor could such a cradle obviously be employed as effectively as mine in rescuing persons falling into the water, which is one of the objects of my invention.

I claim as my invention—

A marine cradle entirely surrounding a boat to be launched from or hoisted to a vessel, con-

structed as described, in combination with a suitable hoisting apparatus, as and for the purpose set forth.

W. W. HANNAH.
